CLAIM

The ornamental design for a cable tie, as shown and described.

DESCRIPTION

FIG. 1 is a perspective top view of a cable tie;
FIG. 2 is a perspective bottom view of the cable tie of FIG. 1;
FIG. 3 is a right side elevation view of the cable tie of FIG. 1;
FIG. 4 is a left side elevation view of the cable tie of FIG. 1;
FIG. 5 is a rear end view of the cable tie of FIG. 1;
FIG. 6 is a front end view of the cable tie of FIG. 1;
FIG. 7 is a top view of the cable tie of FIG. 1;
FIG. 8 is a bottom view of the cable tie of FIG. 1;
FIG. 9 is a cross-sectional side view of a portion of the cable tie that is located between a set of markings 9 in FIG. 7;

FIG. 10 is a perspective top view of a portion of the cable tie that is encircled by broken lines 10 in FIG. 1; and,
FIG. 11 is a perspective bottom view of a portion of the cable tie that is encircled by broken lines 11 in FIG. 2.

Broken lines are used to illustrate portions of the article of manufacture that form no part of the claimed design. Furthermore, the broken lines 10 in FIGS. 1 and 10 and the broken lines 11 in FIGS. 2 and 11 are boundary lines that form no part of the claimed design. The markings 9 in FIG. 7 are also boundary lines form no part of the claimed design. A separation and a bracket are used in the drawings to indicate that a precise length of the cable tie is not claimed. The separation and the bracket in the drawings form no part of the claimed design.
